VIBRATOR DEVICE

Hans Bartels and Alfred Leifer, Berlin, Germany, assignors to Telefunken Gesellschaft für Drahtlose Telegraphie m. b. H., Berlin, Germany, a corporation of Germany

Application October 4, 1939, Serial No. 297,880
In Germany October 5, 1938

1 Claim. (Cl. 200—166)

This invention is concerned with vibratory choppers designed to chop or interrupt a direct current to result in an alternating current. In the use of choppers of this kind, with a view to raising the efficiency, the intervening space between the contacts must be made comparatively small (from .05 to .1 mm.). Moreover, when the contact pieces come together they should snugly engage throughout their whole surface. In order to avoid rebounds or thumping the biasing tension of the counter spring as a general rule must have a definite value; hence, not only the distance, but also the biasing tension must be adjusted.

A modern and widely used form of construction of a chopper is illustrated in Fig. 1 (the exciting coil having been omitted in the drawing). Referring to Fig. 1, 1 denotes the vibratory spring, 2 the contacts, 3 the counter spring, 4 the abutment or stop designed to prevent the counter spring 3 from deflecting in the direction of the vibratory spring. The distance between the working contacts 2 as a general rule is adjusted by adjustment of the abutment 4, the biasing of the spring 3 against the abutment 4 having to be set by adjustment of the spring 3 to the proper value. Now, such adjustment involves the drawback that one of the contact supporting springs or blades must be bent. However, inasmuch as this spring 3 has elastic properties this involves a chance of later changes in the properties of the spring 3. This drawback is obviated by the invention.

According to the invention the counter springs with their abutments are inter-connected outside the union joining all of the spring blades and the insulation parts. As a result the position relative to the vibratory spring of each of the connecting points of a counter spring and abutment may be altered.

Fig. 2 shows an exemplified embodiment of the invention. The abutment 4 and the contact spring 3 no longer are screwed together by screw 7 with the vibratory spring, but they are held above the screw union of the whole spring packet in a distinct supporting member 5. It will be readily seen that the bias tension of the spring 3 may be adjusted by bending the abutment 4 to any practically desired value and that inde-

pendently thereof the position of the working contacts 2 to each other may be adjusted by bending the support 5. Hence, it is no longer necessary to bend the spring 3.

5 In order that the counter spring 3 may be made of adequate constructional length it will be advantageous to bevel or chamfer the insulated layers 6 between the vibratory spring and the counter spring on the end facing the support 10 so that the base points of the vibratory spring and the counter spring will come to lie roughly at the same level.

It is not absolutely necessary that the support 5 should be screwed together with the vibratory 15 spring and the insulation parts by the screw 7, for it is also feasible to dispose the support shiftably outside the said union, say, by means of a screw.

What may also be mentioned is that the counter spring 3, Fig. 2, as illustrated, is preferably fastened on the side of the support facing the vibratory spring in order that the thickness (of the wall) of the support need not be taken into consideration when choosing the distance of the 25 spring.

We claim:

In a current interrupter device, a pair of co-operating contact elements, a resilient vibratory reed having one of said contact elements mounted thereon, an insulating supporting block, means for mounting the vibratory reed on one face of said supporting block, an adjustable arm one end of which is fixed to the opposite face of said supporting block, a counter reed having the other 30 of said contact elements mounted thereon, means for attaching the counter reed to the free portion of said adjustable arm, a stop member also mounted on the free portion of said arm and adjustable relative to the counter reed so as to 35 limit to any desired amount the deflection of the counter reed in the direction of the vibratory element, said arm being arranged to be adjusted so as to adjust the position of both the counter reed and the stop member as a unit relative to the vibratory reed without affecting the adjustment of the stop member relative to the counter 40 reed.

HANS BARTELS.
ALFRED LEIFER.
